UNITED STATES PATENT OFFICE.

JOSEPH J. IGLEHART, OF COLUMBIA, MISSOURI, ASSIGNOR TO HIMSELF
AND WALTER W. GARTH, OF SAME PLACE.

AUTOMATIC LOCKING-STAY FOR DESK-LIDS.

SPECIFICATION forming part of Letters Patent No. 254,324, dated February 28, 1882.

Application filed August 24, 1881. (No model.)

To all whom it may concern:

Be it known that I, JOSEPH J. IGLEHART, of Columbia, in the county of Boone and State of Missouri, have invented a new and Improved 5 Automatic Locking-Stay for Desk-Lids, of which the following is a full, clear, and exact description.

The object of this invention is to provide a self-locking stay or support for desk-lids, awnings, sky-lights, transoms, &c., that will lock them open and closed and support them when open.

The invention consists of two flat plates pivoted together at their overlapping ends so 15 that they may be folded upon and parallel with each other or be opened and extended in a straight line; and it consists, further, of a movable locking-pin held in a socket or opening in one plate and adapted to engage in a socket 20 in the other plate to lock the two together in a folded or open position; and it further consists of a stop to prevent the desk or other article from locking when closed, all of which will be hereinafter set forth,

25 Figure 1 is a sectional side elevation of an open desk with my improved stay and lock in position. Fig. 2 is a sectional side elevation of the same closed and locked. Fig. 3 is a front elevation of an open desk with my improved device in position, on line $x-x$, Fig. 1. Fig. 4 is an elevation of the key used in unlocking the device from a closed position. Fig. 5 is a sectional side elevation of an open desk with a modified form of my device in position, 30 on line $z-z$, Fig. 7. Fig. 6 is a sectional side elevation of the same closed and locked. Fig. 7 is a front elevation of an open desk with my modified stay and lock in position, on line $y-y$, Fig. 5. Fig. 8 is an elevation of the key used 35 in unlocking my modified device from a closed position.

Similar letters of reference indicate corresponding parts.

In the drawings, A represents the body, and 40 B the lid or cover, of a desk.

C C' represent two flat metal plates or stays, placed face to face and pivoted together by a rivet, a, passing through them within a short distance of their ends. The plate C has a sock-

et or slot, b, in its pivoted end, outside of the 50 rivet a, in which socket or slot b the lock-bolt D is movably held, said bolt D having enlarged heads, c, to prevent its disengagement. The pivoted end of the stay or plate C' is cut away on one edge into a half-elliptic curve, d, 55 at either end of which is formed an L-shaped socket or slot, f f', and the extremity of the plate C', beyond the socket f', is formed into a hook, g, to prevent the said supporting-plate C' from turning on the pivot a beyond the 60 lock-bolt D, or, rather, to secure the engagement of the said bolt D in the socket f' whenever the device is closed. The pivot a is passed about centrally through the elliptic d, half-way between the sockets f f'. The free ends of the 65 plates or stays C C' are pivoted, the one on the inside of the desk-body A and the other on a cleat, B', on the inside of the lid B, in such a manner that the hooked extremity g of the stay C' is downward when the desk-lid B is open, 70 as shown in Fig. 1. When the lid B is raised and the stays C C' are extended, as shown in Fig. 1, the bolt D falls into the socket f, and thereby holds said stays C C' immovable in line and supporting the lid B in an open position. 75

When it is desired to close the lid B the operator lifts the lock-bolt D from the socket f and presses said lid B down, thereby causing the stays C C' to incline inward at their point 80 of connection, as indicated in dotted lines, Fig. 1, and their other ends to be approached to each other. As the closing movement of the lid B continues, the lock-bolt D rests upon and is held firmly in its socket b by the elliptic 85 curve d of the stay C' until the desk is fully closed. Then said bolt D falls into the socket f' of the stay C', and thereby holds the stays C C' folded and the desk-lid thereby locked. It is necessary, in order that the lock-bolt D 90 may enter by its gravity the socket f', that the stays C C' be held on a slight incline when closed, and hence a supporting-stud, E', is projected from the inside of the desk A to prevent the undue depression of the pivoted and locked ends of said stays C C'. On the inside of said desk A, near its front, is pivoted a stop, F, of sufficient length for its point to extend above 95

the desk-body, whereby the lid B may be prevented from fully closing and from locking.

From either side of the lower end of the stop F there extends a hooked lug, h, one of which 5 engages over or upon a pin, i, projecting inward from the side of the desk A, and thereby retains said stop F in an upright position, as shown in Fig. 1, while the opposite lug h engages against said pin i when the lid B is 10 closed and holds said stop F in a nearly horizontal position, convenient for use, as shown in Fig. 2.

In order to unlock the locking-stays C C', and consequently the desk, a double-bitted key, 15 G, is introduced into the key-hole k, so that its end shall rest in the grooved plate E, and turned so that its bits shall straddle the edges of the stays C C' and take against each end of the lock-bolt D. Then the said key G is turned 20 so as to lift the lock-bolt D out of the slot f', that the stay C' may be turned on its pivot a, and the desk shall be opened.

In Figs. 5, 6, and 7 is shown a modification of my improved stay and lock, wherein the stays 25 H H' overlap each other and are held together by a pivot, m. The stay H has secured upon it a spring, I, from one end of which projects at right angles a locking-pin, I', whose point rests in a hole or socket, n, made in said stay 30 H, near its edge. The stay H' has formed in it two holes or sockets, o o', placed diagonally across the face of said stay H', near its opposite edges, into which sockets o o' the locking-pin I' is forced by the spring I, for locking the 35 said stays H H' on the opening or closing of the desk, as the case may be. When the lid B is raised, as shown in Fig. 5, the holes n o of the stays H H' respectively coincide with each other, and the pin I' is then forced by the spring 40 I through both sockets n o, thereby firmly locking said stays H H' open.

In order to close the desk-lid B the operator takes hold of the hooked extremity p of the spring I—which extremity p is so formed to afford a convenient handle or hold to the operator—and, pulling upon said extremity p, disengages the pin I' from the socket o. Then on 45 pressing down the lid B the stays H H' are gradually folded together until the said lid B

is closed, when, the sockets n o' being coincident, the locking-pin I' is forced into the socket o' by the spring I, thereby locking the desk.

In order to open the desk, the operator introduces the single-bitted key L through the key-hole s until said key L rests in the guard t. 55 Then said key L is turned so that its wedge-shaped bit u shall pass between the spring I and its stay H, and, forcing the former out, thereby cause the withdrawal of the locking-pin I' from the socket o', so that the lid B may 60 be raised.

Having thus fully described my invention, what I claim as new, and desire to secure by Letters Patent, is—

1. An automatic stay and lock for desk-lids, 65 consisting of two plates pivoted together at their overlapping ends and provided with a two-fold locking mechanism at the said overlapping ends for locking them together in either an extended position or in a folded position, 70 whereby the lid is adapted to be supported when raised and locked when lowered, substantially as shown and described.

2. An automatic stay and lock for desks, &c., 75 consisting of two plates pivoted together at their overlapping ends, one of the said plates being provided with a locking-pin working in a slot and the other with a locking-socket on each side of the pivot that connects the two plates, substantially as and for the purpose set 80 forth.

3. In an automatic desk stay and lock, the combination, with the stay C, provided with the slot b, and the sliding locking-bolt D, of the stay C', provided with the locking-sockets f f', 85 and hook g, the said plates being pivoted together at their overlapping ends, substantially as and for the purpose set forth.

4. The combination, with the desk stay and lock, substantially as herein shown and de- 90 scribed, and desk A, of the pivoted stop F, provided with lugs h and pin i, substantially as shown, whereby the desk-lid may be prevented from locking, as set forth.

JOSEPH JAMES IGLEHART.
